UNITED STATES PATENT OFFICE.

REGINALD H. FILMER, OF LONDON, ENGLAND.

FOLDING BOX.

SPECIFICATION forming part of Letters Patent No. 587,804, dated August 10, 1897.

Application filed December 28, 1896. Serial No. 617,260. (No model.) Patented in England October 29, 1896, No. 24,126.

To all whom it may concern:

Be it known that I, REGINALD HARRY FILMER, a subject of the Queen of Great Britain, residing at London, England, have invented 5 certain new and useful Improvements in Folding Boxes Made of Cardboard, Leather-Board, and such Like Materials, (for which I have obtained Letters Patent in England, No. 24,126, dated October 29, 1896,) of which the 10 following is a full, clear, and exact description.

The invention has for its object improvements in folding boxes made in one piece of cardboard, leather-board, and such like materials, with a view to obtain simplicity of 15 construction combined with facility for erecting the box for use and for folding the same for packing or storing.

My invention is illustrated in the accompanying drawings, in which—

Figure 1 is a plan of the blank shaped and creased or scored according to my invention and provided with a lid or cover and small flaps around the top of the body, as is sometimes done. Fig. 2 is a plan of the box erected for use and with the lid or cover open and turned back. Fig. 3 is a cross-section of the same. Fig. 4 is a plan, and Fig. 5 is an end view, of the box partly folded; and Fig. 6 25 shows the same completely folded for packing or storage. Figs. 2 to 6 are drawn to a larger scale than Fig. 1.

The blank (see Fig. 1) is cut to the shape required and scored or creased on lines a a b b 35 at the junction of the bottom c with the sides d d' and inner end flaps e e , on the lines d^2 at the junction of the sides d d' with the outer end flaps f f , on the line d^3 at the junction of the top of the side d with the small flap g , on 40 the line d^4 at the junction of the side d' with the lid or cover h , on the lines f f' at the junction of the tops of the outer end flaps f f' with the small flaps f^2 f^2 , and on the lines g g' at the junction of the lid or cover h with the descending small outer flaps g^2 g^2 . The 45 blank thus scored or creased is folded on the lines of the said creases or scores to produce a box and lid or cover, as is well understood.

I would here remark that the blank as above 50 described is of known construction and forms no part of my invention separately considered, and I would further remark that the improved box may be made without the flaps f^2

g and lid or cover h , and it may be used with a separately-formed lid or cover. 55

According to my present invention I also score or crease the blank on the lines i i , which for convenience of manufacture are carried across the inner end flaps e , as well as the outer end flaps f and small top flaps f^2 , although the portions of said scorings or creasings i i across the outer end flaps f and small top flaps f^2 are alone used. I further, according to the substance of the material used, make one or more scores or creasings j across 60 the center of the bottom c and inner end flaps e e with a view to enable such parts to be folded on said line j either downward, as shown in the drawings, or in the contrary direction. The inner end flaps e e for packing 65 or storage are folded inward on the lines b , as shown. I also, after having folded the inner end flaps e e inward, cement, rivet, or otherwise fasten the overlapping portions of the outer end flaps f f together and fold them 70 either inward, as shown, on the lines i i or outward, if desired. The blank may also be perforated at k k on the inner and outer end flaps e e f f , as shown, or in other convenient 75 arrangement and tapes or cords l , knotted at one end, threaded through such holes, as shown in Figs. 2 to 5, so as to afford facility for holding the inner end flaps e e against the outer end flaps f f , thus fixing the parts in 80 position for use, and at the same time these 85 tapes or cords may be used for tying the lid or cover on the box and for carrying the same.

Having fully described my invention, what I desire to claim and secure by Letter Patent is— 90

The herein-described folding box, comprising the undivided bottom c and integral inner end flaps e , continuously scored transversely at j , the sides d , d' each having integral outer end flaps f scored at i , the said bottom, sides and end flaps being scored so as to permit them to be set up in box form and permit of the folding of the box, when set up, along the lines of the scorings j and i , the scorings i , when the box is set up or folded 100 being alined with the scoring j in the end flaps, substantially as set forth. 95

R. H. FILMER.
